R. F. Bourne

UNITED STATES PATENT OFFICE.

LOUIS KNEE, OF NEW YORK, N. Y.

FELT WELT AND METHOD OF MAKING SAME FOR GLOVES AND THE LIKE.

1,231,382.

Specification of Letters Patent. Patented June 26, 1917.

Application filed December 20, 1916. Serial No. 137,950.

To all whom it may concern:

Be it known that I, LOUIS KNEE, a citizen of the United States, and resident of New York city, borough of Manhattan, in the county of New York and State of New York, have invented certain new and useful Improvements in Felt Welts and Methods of Making Same for Gloves and the like, of which the following is a specification.

10 The object of my invention is to provide welts adapted to be sewed in the seams of gloves and other articles of apparel and which shall be strong and durable, readily manufactured and used, and cheap to manufacture.

My invention comprises novel details of improvement and combinations of parts that will be more fully hereinafter set forth and then pointed out in the claims.

20 Reference is to be had to the accompanying drawings forming part hereof, wherein, Figure 1 is a partly broken side view of a roll of fabric mounted on a core from which a series of welts are to be cut while 25 on the core;

Fig. 2 is a partly broken side view illustrating a completed series of welts on the core;

Fig. 3 is an end view of a portion of Fig. 2;

Fig. 4 is a detail perspective illustrating a portion of several welts upon the core, and

Fig. 5 is a sectional view illustrating the manner of attaching the fabric on the core 35 to be wound for making the welts.

The numeral 1 indicates a core shown in the form of a tube, which may be of paper, pasteboard or the like, adapted to support a series of welts side by side. In making 40 the welts a strip of fabric, such as felt, of suitable width and length, indicated at 2 (Figs. 1 and 5), is first wound upon core 1, the inner end of such strip being suitably secured upon the core, as by winding the 45 end portion of the strip around the core and gluing the parts together, as indicated at 3, whereby a fabric roll is mounted upon the core to a suitable diameter according to the length and thickness of the fabric. By 50 preference, the felt, before being wound upon the core, is first treated with a suitable coating preparation α , such as by applying sizing upon both faces of the felt to

strengthen the latter and render it the more suitable as a welt. After the strip of fabric 55 has been wound upon the core, said strip is covered by a binder, such as a layer of winding of paper, indicated at 4, the overlapping ends 5 of which paper are glued together. The roll of covered fabric thus 60 formed is then cut transversely by suitably spaced slits 7, to produce welts 6 of suitable width located in series side by side upon the core, but the core is not cut through whereby it remains within the series of welts to support 65 the latter side by side. The fabric may be cut through the inner winding that is upon the core (Fig. 5), but without cutting through the core, upon any well known cloth cutting machine adapted for such purpose. When the roll is cut to form the 70 series of welts, the paper covering 4 will also be correspondingly cut but will remain surrounding each coil of welt, so that each convolution of fabric on the core forming 75 a welt will be retained by the paper covering from unwinding.

When the welts are to be used, the core 1, carrying the series of welts 6 that are located side by side thereon, may be placed 80 upon any suitable support or spindle, and then the welts may be drawn or unwound from the core successively as required, the covering 4 on each welt first being removed 85 therefrom to permit access to the free end 85 of the welt, the coverings on the several unused welts retaining the latter from unrolling until used.

My improved welts, when made of felt convolutions as described, may be of considerable continuous length, and are adapted to be sewed in the seams of gloves, mittens and analogous articles of apparel, in a well known manner of applying welts to such articles, and said welts may be rapidly applied in such articles. Said welts are economically manufactured owing to their extended lengths, and are much cheaper than leather welts which have been sewed in the 95 seams of gloves, mittens and the like.

It will be apparent that since a series of 100 welts are supplied upon a single core they may all at once be placed with the core upon a support or spindle, to there remain until all the welts are used, thus reducing 105 the handling of welts to a minimum, as

compared with that required where each welt is supplied as a single unit, serving thereby to reduce the cost in using welts.

Having now described my invention what I claim is:—

- 5 1. As a new article of manufacture, the combination of an integral core, with a series of independent welts comprising single fabric convolutions side by side upon said core.
- 10 2. As a new article of manufacture, the combination of an integral core, with a series of independent welts comprising single fabric convolutions side by side upon said core, and bindings secured around said welts.
- 15 3. As a new article of manufacture, the combination of a core, with a strip of felt wound thereon and slit transversely approximately to the core, the core being unsevered.
- 20 4. As a new article of manufacture, the combination of a core, with a strip of felt

wound thereon, a binding secured around such winding, said binding and winding being slit in spaced relation transversely to the core, the core being unsevered.

25 5. The method of making fabric welts consisting in winding a strip of fabric upon a core, winding a binding covering upon said wound fabric and securing the binding thereon, and slitting said binding and the 30 fabric transversely approximately to the core without cutting through the core, providing a series of welts wound side by side upon the core.

Signed at New York city, in the county 35 of New York, and State of New York, this 19th day of December, A. D. 1916.

LOUIS KNEE.
